VALVE BAG

Douglas E. Scott, Chagrin Falls, Ohio, assignor
to The Chase Bag Company, Cleveland, Ohio,
a corporation of Delaware

Application December 18, 1936, Serial No. 116,608

4 Claims. (Cl. 229—62.5)

My invention relates to valve bags and more particularly to paper valve bags intended for the handling of carbon black and other fine material which has a tendency to leak through the ordinary valve.

Heretofore valve bags have been filled through a feed pipe inserted between the usual valve flap and the end flaps. It has also been proposed to provide such bags with a paper valve-sealing tube open at both ends and having its inner end affixed in the valve opening, and the outer end thereof designed to form a sealing closure. However the use of such sealing tubes has proven objectionable due to the fact that the tubes have a tendency to hug the filling spout and prevent the escape of air, thus slowing down filling operations.

The principal object of the present invention is to provide a valve sealing tube which obviates the foregoing objections.

Other objects and advantages of the invention will be apparent from a consideration of the specification in connection with the accompanying drawing, in which:

25 Figure 1 is a plan view of a bag embodying my invention, showing the valve sleeve in extended position;

Figure 2 is a section on line 2—2 of Figure 1, with the filling spout in position;

30 Figure 3 is a fragmentary plan view of the bag showing the valve sleeve partially folded;

Figure 4 is a view similar to Figure 3 showing the valve sleeve completely folded; and

35 Figure 5 is an enlarged section taken on line 5—5 of Figure 2.

Referring more particularly to the drawing 10 denotes a paper bag having the usual valve flap 11, and inner and outer end flaps 12 and 13 40 respectively which close the upper end of the valve when cemented together, by means of a layer of paste 14.

A valve sealing tube 15 of plain kraft paper is inserted into the valve opening and is secured 45 at one side of its inner end to the valve flap 11, by means of a layer of paste 16. The upper edge or face of the flap valve 11 is secured to the inner end flap 12, as by means of adhesive 17. The adhesive 16 and 17 does not extend 50 outwardly very far, thus leaving the outer end 18 of the paper tube 15 free to be folded and tucked into the valve opening after the bag has been filled. Filling of the bag is effected in a customary manner through the opening 19 of

a feed pipe or spout 20 which is inserted into the paper tube 15.

Practice has proven that when a tube such as just described is opened by the packer for the insertion of the filling spout 20, the tube will not stand away from the spout sufficiently to permit the air to escape. In other words the tube will hug the spout so closely that the air is trapped. In this connection it should be noted that the tube must be of relatively thin flexible 10 tough paper to permit of the flap being effectively folded and tucked.

According to the present invention I make the tube 15 of approximately 40 lb. plain kraft paper. Within the tube and affixed thereto by means 15 of a gummy pliable adhesive 21, is a sleeve or lining member 22 of approximately 30 lb. crinkled or crimped or creped kraft paper. When the tube is opened by the packer, the crinkled sleeve and the layer of gummy adhesive functions to 20 hold the tube open and sufficiently away from or out of contact with the filling spout to permit of free escape of air through air space 24 between the sleeve and filler tube. In short the double walled tube is so pliable and of such 25 consistency that it can readily be opened or closed to any desired degree and will remain more or less fixed in such position. The sleeve 22 is preferably co-extensive with the tube 15, and the layer or wall of gummy adhesive 21 preferably covers the entire opposing faces of the tube and its sleeve.

A thumb opening or cut 23 is provided at one side of the tube to facilitate opening thereof.

After the bag has been filled, and the filling 35 spout removed, the tube is preferably first flattened, then the corners 23 are folded downwardly and inwardly as illustrated in Figure 3, and finally the outer end of the tube including the 40 folded corners, is folded downwardly and inwardly and tucked between the body of the tube and the valve flap 11. It should be noted that the outer end of the paper tube 15 extends sufficiently out from the valve opening to provide 45 ample length for the folding and tucking operations just described.

What I claim is:

1. A bag ready for filling and having a bag opening, a paper valve sealing tube open at both 50 ends and having its inner end affixed in the valve opening and having its outer end extending outward from said opening and designed to form a sealing closure at said outer end, said sealing tube having a flexible, pliable crinkled 55

sleeve of less weight than said tube affixed therein.

2. A bag having a valve opening, a valve sealing tube open at both ends and having its inner end affixed to the inside of the walls of the valve and having its outer end extending far enough to fold, there being a space between the tube and the outer edge of the valve adapted to receive the folded end of the tube, said sealing tube having a flexible pliable crinkled sleeve of relatively light material affixed therein, said sleeve being substantially coextensive with and cemented to said tube.

3. A paper valve bag having its valve formed by end flaps, and a paper valve sealing tube open at both ends and inserted between the valve forming flaps and adhered to said flaps

at its inner end, the outer end of the tube extending outward far enough to fold, and there being a space between the outer edge of the end flap and the tube wherein the folded end of the tube may be inserted, said sealing tube 5 having a flexible crinkled pliable sleeve affixed therein.

4. A bag ready for filling and having a valve opening, a valve sealing tube open at both ends and having its inner end affixed in the valve 10 opening and having its outer end extending outward from said opening and designed to form a sealing closure at said outer end, said tube comprising an outer layer of plain kraft paper and an inner layer of crinkled paper, said layers 15 being affixed together by a layer of adhesive.
